UNITED STATES PATENT OFFICE.

ANDREW CHRISTIAN ANDERSEN, OF DETROIT, MICHIGAN, ASSIGNOR TO TERNSTEDT MANUFACTURING COMPANY, OF DETROIT, MICHIGAN, A CORPORATION OF MICHIGAN.

WINDOW REGULATOR.

Application filed July 14, 1924. Serial No. 725,759.

This invention relates to window regulators—especially a rear quarter window regulator.

It is the object of the present regulator to provide a rear quarter regulator which has a control handle that runs along the window well and may be locked in various positions along the sill to get the window in raised or partially raised position.

10 Rear quarter windows do not present the same problem as do the door windows and the windows in the forward part of the car. In nearly all cars the rear quarter windows can be let down part way on account of 15 the wheel housing. In quite a few cars, it is still customary to use the window straps because they are cheap, the window is not so often opened, and because the regulator handle adjacent the rear quarter is a source 20 of annoyance especially to women in catching and tearing their clothes.

One cheap form of regulator which is in quite extensive use is one that has a vertical notched bar for receiving a locking device 25 which is connected to the window sash. The counterbalancing spring and lever tend to lift the window. A regulator of this kind is objectionable because the bar is always exposed and the lever action is never directly controlled but only by raising or lowering the sash.

It is the object of the present invention to provide a regulator in which the lifting lever is directly controlled by a slide that 35 runs transversely across the sill. Such a control is not broadly new for apparatus to affect this action by means of a system of levers, as shown in the prior Heintz Patent No. 1,436,407. This, however, involves 40 a system of levers which is very much more expensive to contract than the invention now about to be described.

In the drawings:

Fig. 1 is an inside elevation of the car 45 equipped with my improved window regulator.

Fig. 2 is a view of the inside of the arm rest board showing the new regulator in place.

50 Fig. 3 is a section taken on the line 3—3 of Fig. 2.

Fig. 4 is a detail of the slide.

Fig. 5 is a section on the line 5—5 of Fig. 4.

Fig. 6 is another detail of the slide.

The arm rest board *a*, which is sometimes called the lock board, is notched as at *b*. Over this notch is fitted a plate *c* which is secured to the arm rest board by screws *b*. This plate has a punched out stop *d* for the 60 lifting lever *e*. This lifting lever is pivoted to the plate by special machine stud *f* which is slotted as at *g* to receive one end of the spiral counterbalancing spring *h*; the other end is looped over the turned over arm *i* 65 of the regulator plate. The stud *f* is secured to the lever *e* so as to turn therewith, hence the movement of the lever tends to either wind or unwind the counterbalancing spring. On the end of the lever is a roll *j* which fits 70 into the channel *k* of the window sash.

There is secured under the sill or garnish moulding *m* a channel-like track *n*. The lower flange of this track is notched as at *o*. A carriage or slide *p* runs in this channel 75 track. This slide comprises a strip of metal bent out as shown in Fig. 5, and having riveted to its ends a pair of fibre strips *q*. The center offset portion *r* forms a housing to receive the operating handle *s*. This is 80 in the form of a stamping which forms a clutch or dogging device. This dogging device has a tooth *t* struck out from the stock. The wire spring *u* is supported on the lugs *v* struck out from the carriage housing; the 85 ends are looped over the tooth *t* and thereby tend to keep the dog in its vertical position. In this position the tooth *t* is arranged to engage in one of the notches *o* of the lower flange of the track, as is shown in Fig. 3. 90 However, as soon as one grasps the handle the dogging device tends to rock on one of the nubs *w* which are located on the forwardly and rearwardly extending arms of the stamped metal dog. This is well illustrated 95 in Fig. 6. This, one will see, automatically releases the tooth *t* from the notch and permits the handle to be operated to slide the carriage.

The depending web *y* of the carriage is 100 pivoted to the lifting lever *e* near the end thereof. This link in connection with the slide makes it a very simple and inexpensive regulator; there are only two parts to be connected to the arm rest board, to wit: 105 the regulator plate and the track. The slide travels in a horizontal path on a track which is completely concealed in the window well. I am aware that it is not broadly new to use a lever to raise or lower the lifting 110

lever, but as far as I am advised a regulator of this type has not been successful for obvious reasons. The idea of a horizontally guided slide having a direct draft and thrust connection with the lifting lever, I believe to be a new and valuable improvement, because a relatively cheap construction, because the operating track is completely concealed and because the operating handle is in a position not to interfere with the occupants of the rear seat.

What I claim is:

1. A window regulator having in combination, a track arranged to be located in a substantially horizontal line along the top of the window well, a hand-controlled slide arranged to slide along the track and to lock in various intermediate positions, a window lifting lever arranged to be pivotally supported by the board at the side of the window well and having its free end in slidable engagement with the bottom of the window sash, and a direct draft and thrust connection between the slide and the said lever.
2. A window regulator having in combi-

nation a track arranged to be located in a substantially horizontal line along the top of the window well, a hand-controlled slide arranged to slide along the track and be locked in various intermediate positions, a window lifting lever arranged to be pivotally supported by the board at the side of the window well and having its free end in a slidable engagement with the bottom of the window sash and a link directly connecting the slide and the lifting lever.

3. A window regulator, having in combination a track arranged to be located in a substantially straight line along the top of the window well, a hand-controlled slide arranged to slide along the track, a window lifting lever arranged to be pivotally supported by a board at the side of the window well and having its free end in slidable engagement with the bottom of the window sash, and a direct draft and thrust connection between the slide and said lever.

In testimony whereof I have affixed my signature.

ANDREW CHRISTIAN ANDERSEN.
